1,981,572

METHOD OF HEAT TREATING
HYDROCARBON OIL

Willis F. Sims and Venus U. Cloer, Wichita Falls, Tex., assignors to Panhandle Refining Company, Wichita Falls, Tex., a corporation of Texas

Application April 9, 1930, Serial No. 442,871

2 Claims. (Cl. 196—61)

Our invention relates to the treatment of hydrocarbon oils and especially to such treatment when carried on for the production of motor fuel from petroleum by the process commonly known as cracking. The present application is closely related to our prior copending applications, Serial No. 254,753, filed February 16, 1928, which has matured into Patent Number 1,948,890, Feb. 27, 1934; No. 361,015, filed May 6, 1929, which has matured into Patent Number 1,821,116, Sept. 1, 1924, and No. 409,406 and No. 409,407, filed November 23, 1929, which have matured into Patent Number 1,930,372, Oct. 10, 1933, and Patent Number 1,918,670 July 18, 1933, respectively; and the invention described and claimed herein is in the nature of an improvement over the inventions disclosed in said prior applications. In the earliest of these applications Serial No. 254,753 we have described and claimed an improved method of cracking under sub-atmospheric pressure or vacuum. In our application, Serial No. 361,015, we have described and claimed apparatus to be used in connection with said method. In our application, Serial No. 409,406, we have claimed particularly the mechanical arrangement of the preheating furnace and the cracking still in one unit. In the last application mentioned, No. 409,407, we have described and claimed the arrangement of the fractionators and the absorption tower. Our present invention has for its object particularly the improvement of the preheating and cracking apparatus and the method of operating the same. While it is true that a certain amount of cracking might take place in a flashpot, nevertheless we find that by giving a particular design to our flashpot, or by adding to or substituting for the same an element provided with supplemental heating and agitating means, the percentage of conversion is increased as well as the efficiency and rapidity of operation. Accordingly, we attain our object by inserting at the preheating end of the system a tube or pot heated by a furnace or the equivalent, and provided with mechanical means for stirring and agitating the vapors in the pot, while maintaining a layer of the same of uniform thickness over the entire inner surface of the walls thereof. This piece of apparatus may be substituted for the flashpot, or may supplement the flashpot, but in any case its output is connected with the input of the cracking still and the vacuum or sub-atmospheric pressure maintained on the cracking still is extended back to the hot tube and on through the latter to the separate flash-

pot if such be employed. As a matter of convenience, we may use for our purpose known structures, such for example as that disclosed in U. S. Letters Patent No. 1,732,805, granted October 22, 1929, to E. C. D'Yarmett. As will sufficiently appear hereinafter however, we do not use the same type of tube or cooperating parts as in that patent, but have specially designed our tube so as to attain our own object.

Our invention is illustrated in the accompanying drawings, in which

Fig. 1 is a diagram showing a hot tube used instead of a flashpot.

Fig. 2 is a sectional view of a furnace and hot tube unit of one type which we may employ in place of the flashpot.

Fig. 3 is a horizontal section on the line 3—3 of Fig. 2 looking in the direction of the arrows.

Fig. 4 is a vertical sectional view of a furnace and hot tube of a type we may employ with the flashpot.

Fig. 5 is a diagrammatic view of the preheater, cracking coil, hot tube, and flashpot, of the type shown in Fig. 4.

Referring to the drawings and first to Fig. 1, 56 is the tubular cracking still, inclosed within a furnace 2, heated by oil burners 62; 57 is the pre-heating coil heated in part by burners 61 and in part by waste gases and products of combustion passing from the furnace 2 through openings 63 into the preheater chamber 2a and thence into the stack 60 through either one or both of the flues 58 and 59. By adjusting the dampers in the flues, the amount of heat energy absorbed through the coils 57 may be regulated.

Charging stock is fed into the preheater 57 through pipe 53 by a pump 54; and the preheated oil passes out through the pipe 52 and through a branch pipe (both of which are valved, as indicated at 23 and 38a) to the intake pipe 111 of the hot tube 110. This tube is shown on a larger scale and in section in Fig. 2. Referring to said figure, 111 is the intake, 55 is the output leading to the cracking coil 56 in Fig. 1; 101 is the furnace, 102 is the stack, 103 is the down draft chamber containing the hot tube 110, around which all the products of combustion and heated gases from the furnace are compelled to pass before reaching the stack 102. It should be noted that the stack 102 may be the same in practice as the stack 60, or they may be two separate flues in one stack.

104 is an oil burner in the furnace 101, controlled by a valve 105. 112 is a central shaft extending from end to end of the hot tube 110, jour-

90

95

100

105

110

nalled in bearings outside the furnace, one of which includes a stuffing box 113, to permit the extension of the shaft 112 outside the foot of the tube to receive power through gears 114 from a shaft 115 driven by a motor 116. The shaft 112 carries paddles or blades 120 extending across the diameter of the tube as shown in Fig. 3 and when rotated by the motor 116 adapted to maintain a rapid, turbulent, swirling motion of all vapors in the tube, together with a thin film of oil vapors in contact with the inner wall of the tube all around, to receive heat therefrom. The action of these blades is centrifugal and results in every portion of the vapors being uniformly exposed to the heat of the walls. The head of the hot tube is provided with a chamber or trough 117 having a draw-off tube 118 connected to it and provided with a valve 119. Any liquid which separates out and is not vaporized will be carried to this trough 117 at the top of the tube and will be drawn off through the residue draw-off line 118.

Referring to Figs. 4 and 5, the furnace 101, the cylindrical hot tube 110a, the shaft 112a, stuffing box 113a, and the blades 123, are all the same as previously described. In this form, however, there is no trough at the head of the tube. Vapors only from either the flashpot or the vaporizing unit (hot tube or still) enter this cracking tube 110a through the vapor inlet line 121 and pass upward to the vapor line 122, the revolving blades 123 causing a turbulent flow of the vapors.

It will be noted that in the arrangement of Figs. 1 and 2, and also in the arrangement of Figs. 4 and 5, the output of the hot tube, through pipe 55, or pipe 122, is the same, that is to say heated vapors which have been partly cracked. After leaving the hot tube, 110 or 110a, the vapors are passed to the tubular cracking still 56 (Fig. 1) where the cracking is completed, still under a vacuum. From the cracking still 56, the cracked vapors are carried through a plurality of fractionators 6, 7, 8 and an absorption tower 11, the condensed oils from the fractionators passing to a suitable separator 10 and receiver, while the lighter vapors carried off with heavier fractions are recovered in the absorption tower 11 and returned to the last fractionator 8 to be therein released, and condensed, and passed to the separator 10. In the top of each fractionator is a heat exchanger 28, 27, or 26. Make-up oil, combined with uncracked heavier fractions, is pumped back through these heat exchangers in series, abstracting heat from the vapors in the respective fractionators, and being finally delivered to the flashpot or hot tube 110 as preheated oils at a high temperature. The entire system is under a vacuum on the outgoing side due to pump 14, that is to say, from the flashpot through the hot tube 110, cracking coil 56, and fractionators 6-7-8 to the condenser or cooler 9, and separator 10; but the refluxed oils which are pumped back through the heat exchanging coils in the fractionators, are under pressure from the pump 15 which propels them, until they are released into the flashpot as controlled by a valve 38 thereat.

The hot tube 110a is preferably vertical, and contains an axial shaft 112a rotated by external power, and carries radial blades 123 extending across the internal diameter of the tube, which are constantly rotated, causing a turbulent flow of vapors and therefore a high heat transfer to vapors being cracked. After being thus expanded into vapors and partially cracked in the hot tube as such, these vapors pass to the cracking coil as before and so on to the fractionators.

While it is true that a certain percentage of cracking occurs whenever oils are heated, it is also true that the product is both uncertain and unsatisfactory unless the conditions are fixed, and particularly the amount of heat energy communicated to each part of the body of oil under treatment, which should be uniform, and the pressure thereon. The peculiar virtue of a hot tube of the type described, with rotary paddles, is that instead of massing the oil in a body requiring deep penetration of the heat waves, whereby uniform heating is of course impossible, we can form a thin film around the inside of the hot tube which is easily and uniformly penetrable by the heat energy communicated through the walls of the tube while at the same time, owing to the motion of the paddles, the vapors passing through are in a turbulent state of flow, and therefore in the best condition to absorb heat as they are brought into contact with the tube walls. This much of itself however would not be sufficient for our purpose, inasmuch as the vapors initially produced in our system are supposed to contain all the fractions of the charging or make-up oil flashed into vapor simultaneously. The characteristic feature of our system by which we accomplish this is to preheat them under pressure, as already stated, and then admit them to the expansion chamber, which in this case is the hot tube, and thence to the cracking still, under a vacuum.

As an alternative to the foregoing, and in order to insure complete vaporization of the charged oil or make-up oil, we may use a flashpot in conjunction with the hot tube, all oils to be cracked, whether raw charging oil or make-up or refluxed fractions, being first flashed into vapors in the flashpot and then passed to the inlet of the hot tube as vapors, whereby the percentage of unsaturates and aromatic compounds is increased. The purpose in mind in designing this entire system has been to produce one hundred percent of cracked products as unsaturates and aromatics, or in other words high grade motor fuel.

The vapors from the hot tube 110 are drawn through the cracking tube 56 preferably at a temperature of 1000° F. to 1200° F., and a pressure of 6 to 14 pounds absolute is maintained on said tubes by the vacuum pump 14. This low pressure affects also the hot tube, and lowers the temperature at which the cracking reaction takes place. It also accelerates the velocity of the vapors, considering a constant gallonage of raw oil charged, as compared with a system operated at or above atmospheric pressure. This effect extends also back to the hot tube 110a, wherein a double effect is produced by the blades 123 and the low pressure combined. The resultant effect is to speed up the operation of cracking beyond what has heretofore been possible since the vacuum pull on the hot tube 110a and the tubes 56, causes a rapid flow of vapor through them, while the paddles 123 in the hot tube by forcing the vapors against the tube walls, keep up the temperature of the vapors and prevent the loss which would otherwise occur due to too rapid travel of the vapors through the system. Thus the result produced by our combination is more than the sum of the separate results of the use of a hot tube and the maintenance of a sub-atmospheric pressure taken separately. We have discovered that by maintaining a vacuum in the vapor phase we can advantageously increase travel, and by providing means to supply more heat, or to expose more vapors in their travel to the heat, we can not only maintain

the speed of travel, but also maintain or increase the rate of conversion per unit of time or per unit of travel, or both. If the tube 110a had sufficient capacity, or if a battery of said tubes be employed, the cracking tube 56 might be dispensed with without altering the principle involved or the improved result attained, which is due to the combination of more efficient heating with the low pressure and increased travel.

The vacuum pump 14 is located at such a position, with suitable connection lines 30, 39, 40, 42, and valves 3, 4, 5, 19, 46, 20, 21, and 25, that the vacuum may be applied at the discharge from the tubes in the heating zone 2, afterward pumping the vapors so removed from the tubes to cooling and separation tower 6, or the vacuum may be applied on the separator drum 10 and the vapors so removed may be discharged into the absorption tower 11.

The vapors entering the cooling and separation tower 6 may be at or below atmospheric pressure, depending on the point at which the vacuum is applied to the system, and will be at an elevated temperature, preferably from 1000° F. to 1200° F., depending on the temperature found most suitable to give the largest practical yield of gasoline or related light oils. Because of this elevated temperature of these vapors they contain considerable quantities of heat that must be removed before the products of the reaction produced in the tubes can be condensed and made stable under atmospheric conditions. This heat is removed in two ways; (1) by causing the hot vapors to come in contact with a downward flow of liquid oil, drawn from the bottom of cooling and separation tower 7 by pump 13, and discharged through valve 18 to tower 6, preferably contacted with the hot vapors over a series of baffle plates placed in this tower; and (2) by causing the vapors to come in contact with heat exchanging coils 26 placed in this tower, through which oil of relatively lower temperature than the vapors is caused to flow by pump 15. This causes the heat to be utilized (1) in vaporizing the incoming oil from tower 7, and (2) in the absorption of the heat by the cooler oil flowing in the cooling coils. This cooling effect will cause a heavy residue to collect in the bottom of the cooling and separation tower 6 which is removed from the system by pump 12.

The vapors from tower 6 enter the tower 7, at or below atmospheric pressure depending on the point at which vacuum is placed on the system and in tower 7 they are further cooled and fractionated. This tower is preferably of the bubble type. The cooling is effected by causing the vapors to come into contact with heat exchanging coils 27, through which oil of relatively lower temperature than the vapors entering the tower is caused to flow by pump 15. The cooling in this tower is carried to such a point that a large portion of the vapors entering it are caused to condense to liquid. This liquid is drawn from tower 7 by pump 13 which discharges a part of it into tower 6 at 18 and a part through the coils 26. Valves 18 and 47 are so located on the discharge line from pump 13 that all or any part of the liquid from the bottom of the cooling and separating tower 7 may be caused to discharge into either the tower 6 or the coils 26.

The vapors from the tower 7 enter another tower 8 at or below atmospheric pressure depending on the point at which the vacuum is applied to the system, and in tower 8 they are further cooled and fractionated. This tower is preferably of the bubble type. Cooling is effect-

ed by causing the vapors to come in contact with the coil 28 through which oil at a lower temperature than the vapors is caused to flow by pump 15. This cooling allows a considerable portion of the vapors to be condensed and the condensed fractions are removed from the bottom of the tower through the heat exchanger 17 by the pump 15. A part of the oil, after having been cooled by passing through the heat exchanger 17, is discharged by pump 15 through valve 31 into the absorption tower 11, and a part of the oil is discharged through coils 28 and 27, through valve 32. Valves 31 and 32 may be so opened or closed as to cause a desired quantity or all to flow in either direction.

The vapors in the tower 8 are also cooled by the liquid from the bottom of the absorption tower 11 which is pumped from tower 11 by pump 16 through heat exchanger 17 where the temperature of this liquid is raised by liquid flowing in a counter current from the bottom of tower 8, and it is then discharged into tower 8 through valve 33. The temperature of the liquid entering tower 8 may be controlled by by-passing the heat exchanger with a portion of the cold liquid from absorber 11. This by-pass may be of any suitable or desired construction, and is shown at x in the drawings. The liquid from absorber 11 contains the very light fractions not condensed by water cooling coil 9. These absorbed light fractions are removed from this liquid on its entrance into tower 8 due to the heat it gains in heat exchanger 17 and the hot vapors entering tower 8.

The vapors from the tower 8 are caused to pass through water cooling coil 9 where they are condensed at atmospheric pressure or lower depending on the point at which the vacuum is applied to the system. This condensate, because of the cooling and separation it has previously had, is gasoline or related light oils and is collected in separator drum 10. This light liquid is removed from the separator drum 10 through valve 29 by a pump not shown in the drawings.

The vapors that collect in separating drum 10 are either drawn from it by vacuum pump 14 or are caused to pass into absorbing tower 11 by reason of their own pressure. This also depends on the point at which the vacuum is applied to the system. These vapors flow in a counter-current to the cooled liquid from the bottom of the tower 8 and the lighter gasoline or related lighter oils are absorbed in this liquid. The tower 11 is preferably of the bubble type.

The fixed gases pass from the tower 11 through line 47 to the atmosphere, or to burners under the furnace, or to commercial gas lines.

The bottoms from tower 8, either with or without make-up oil, delivered through line 34 and valve 35, not required as absorption oil in the tower 11, are returned to the system and used as cooling oil in coils 28, 27, and 26. The line conducting this oil to coils 28 and 27 has valves 36 and 37 so situated that all or any part of this liquid can be caused to flow through them. The heated liquid from coils 26 is conducted through line 22 and through valves 38 and 38' to the hot tube 110 or the flashpot as the case may be, and the vapor so produced is retreated in the tubes 56 placed in this furnace.

We have not deemed it necessary in adapting the additional element of a hot tube to our system, to vary the type of fractionating, separating, and absorption apparatus employed in our previous systems. The only differences in the sys-

80

tem of Fig. 1, from the cracking still 56 onward, are those which naturally occur in operation or adjustment when the rate of conversion is higher and the initial heating operation more efficiently 5 and perfectly performed. The adjustment of the valves throughout the system will be affected, because there will be less of the heavy fractions to reflux and recrack, there will be a higher percentage of the desired motor fuel in the first 10 run-off, and particularly the percentage of unsaturated and aromatic compounds passing from the separator will be increased and under favorable conditions may reach practically 100%. It will be understood of course that this does not 15 mean 100% of the raw oils, by 100% of the cracked product. The percentage of the raw oil initially charged which will be ultimately delivered as motor fuel will vary, of course, according to the character of the oil used. However, 20 we can show a very substantial improvement in every respect by the use of the process and apparatus described herein, and particularly in the percentage of conversion, and the character of the cracked products.

25 What we claim is:

1. The method of heat treating hydrocarbon oils and of producing motor fuel therefrom, which consists in heating the oils under pressure to distillation temperatures, passing a stream of the 30 oils into a circular flash-vessel under sub-atmospheric pressure, rotating the vapor and residual oils therein at a speed sufficient to confine substantially the entire oil content of the vessel to a film of oil on the inner surface of the vessel and 35

to maintain the oil vapors in said vessel, heating said film to a high temperature through the walls of said vessel at sub-atmospheric pressure, and continuously collecting and drawing off the heated vapors from said vessel under a sub-atmospheric pressure or vacuum, super-heating said vapors in a cracking zone at sub-atmospheric pressure separated from the flash-vessel to complete the cracking operation, and finally fractionating and condensing the same. 8

2. The method of heat treating hydrocarbon oil which consists in heating the oil to distillation temperatures, flashing said oil into vapors in a flashing zone at sub-atmospheric pressure, separating unvaporized liquid oil from the vapors in the flashing zone without cooling, and reheating the separated liquid oil in the flashing zone, taking off the vapors under sub-atmospheric pressure, removing unvaporized oil and heating the vapors (only) in the vapor phase to cracking temperatures under the following conditions: first rotating the said vapors under sub-atmospheric pressure to form a film of the heavier constituents having an extended area under a relatively higher pressure while maintaining the neighboring lighter vapors at sub-atmospheric pressure and applying heat to said film over the entire area, and second passing said vapor through a connected superheated cracking zone while maintaining a sub-atmospheric pressure continuously on said vapors during both steps. 9
